UNITED STATES PATENT OFFICE.

WILLIAM GENTRY SHELTON, OF CHICAGO, ILLINOIS.

MASSAGE INSTRUMENT.

No. 829,742.

Specification of Letters Patent.

Patented Aug. 28, 1906.

Application filed May 25, 1905. Serial No. 262,177.

To all whom it may concern:

Be it known that I, WILLIAM GENTRY SHELTON, a citizen of the United States, formerly residing at the city of St. Louis, in the 5 State of Missouri, now residing at the city of Chicago, in the county of Cook and State of Illinois, have invented a certain new and useful Massage Instrument, of which the following is such a full, clear, and exact description as will enable any one skilled in the art to which it appertains to make and use the same, reference being had to the accompanying drawings, forming part of this specification.

15 My invention relates to massage instruments, and more particularly to improvements in that form of instrument shown and described in application, Serial No. 253,551, filed by me April 3, 1905.

20 In the accompanying drawings, which illustrate an instrument made in accordance with my invention, Figure 1 is a side view, partly in elevation and partly in section. Figs. 2 and 3 are sectional views showing 25 details of construction. Fig. 4 is an enlarged sectional view showing a slight modification. Fig. 5 is a section on the line 5 5 of Fig. 4. Fig. 6 is a top plan view of the parts shown in Fig. 4, and Fig. 7 is an enlarged view of the 30 handle and dial for controlling the movement of the contact device.

Like marks of reference refer to similar parts in the several parts of the drawings.

10 represents the handle, by means of 35 which the instrument is manipulated. Carried by the handle 10 is the casing, consisting of an inner part or frame 11 and an outer part or shell 12. Carried by the casing is the electric motor, consisting of a field 14 and an 40 armature 15.

16 is the commutator of the motor, and 45 17 the brushes. Current is carried to the motor through a flexible conductor 18. This flexible conductor 18 contains two wires 19 and 20. The wire 19 leads to the motor, and the wire 20 returns the current from the motor. The flow of current through the motor is controlled by a switch connected to the wire 20. One part of the wire 20 is secured 50 to a fixed terminal 21 and the other to a movable terminal 22. The movable terminal 22 is provided with a finger-piece 23, projecting out of the handle 10, so that by operating the finger-piece 23 the terminals 22 and

21 can be brought together to complete the 55 circuit through the motor.

Mounted on the shaft 25 of the armature 15 is a fly-wheel 26. In the form of device shown in Fig. 1 this fly-wheel 26 is mounted so as to be movable longitudinally of the shaft 25, but to be incapable of rotation independently thereof. In order to move the fly-wheel 26 along the shaft 25, I provide a rod 27, having a bifurcated end 28, which engages with a grooved collar 29 on the fly-wheel 26. The end of the rod 27 is threaded and passes through a nut 30. This nut 30 is provided with an arm 31, having a handle 32. The arm 31 moves adjacent to a dial 33, which is secured to the handle 10 by means of screws 34 or in any other suitable manner. The nut 30 is provided with a flange 35 at the rear of the dial 33, so as to prevent longitudinal movement of the nut. It is evident that by turning the arm 31 by means of the handle 32 the rod 27 would be moved longitudinally, so as to move the fly-wheel 26 along the shaft 25. The fly-wheel 26 is provided on its face with a projection 36, in which is formed an inclined radial slot 37. In this slot 37 is a ball 38, for which said slot forms a guideway oblique to the axis of rotation of the fly-wheel 26. The ball 38 is rotatably mounted on a stud 39, carried by a connecting-rod 40. On the rod 40 is a ball 41, which is arranged in a seat 42, formed in the outer end of the casing 12. Only half of the seat is formed in the casing 12, however, the other half being formed in a washer 44. This washer 44 is held in place by means of a 90 spring 45 and screw-cap 46. This spring takes up the wear of the parts 41 and 42 and prevents the ball 41 from rattling. In order to prevent the shaft 40 from rotating, I provide the ball 41 with a pin 47, which works in an enlarged opening 48, so as to allow the shaft 40 to have a translatory movement, but to prevent its rotation. On the end of the shaft 40 and at a point a substantially fixed distance from the universal joint composed of parts 41, 42, and 44, above described, is a massage-cup 50 or any other suitable contact member or device. It will be seen that by rotating the handle 32, and consequently moving the shaft 27, the fly-wheel 26 will be 100 moved longitudinally, so as to cause the ball 38 to move toward and away from the center of the fly-wheel 26 in the inclined radial

slot 37. In order to keep the ball in its proper position, I provide in the bottom of the slot 37 a spring 51 and place between the spring and the ball an oil-pad 52. Oil may 5 be supplied to the pad 52 through an oil-duct 53. (Shown in Fig. 3.)

In the modification shown in Figs. 4, 5, and 6 the ball-and-socket joint for the rod 40 in place of being made in the end of the casing 10 12 is made in a tube 55, which slides into the end of said casing. In the end of the casing 12 is a slot 56, part of which is inclined, as shown at 57. Passing around the end of the casing is a ring 58, provided with lugs 59 and 15 60. 65 is a thumb-screw which passes through the lug 59 and is threaded into the lug 60. Between the lugs 59 and 60 is a member 61, carrying a pin 62, which passes through the slot 56 and into an opening 63 in the tube 55. 20 By moving the pin 62 in the inclined part 57 of the slot 56 it will be evident that the tube 55 will be moved longitudinally, and this will have the same effect upon the connection between the rod 40 and the fly-wheel 26 as by 25 moving the wheel, as described above. When the tube 55 has been moved to the desired position, the parts can be clamped by tightening the thumb-screw 65.

Having fully described my invention, what 30 I claim as new, and desire to secure by Letters Patent of the United States, is—

1. The combination with a frame, of a rotary member carried thereby, a contact member, and adjustable operating means between 35 said members, said operating means making sliding connection with one of said members and comprising a part of a pivotal joint one part of which joint is normally stationary on said frame and the other connected with said 40 contact member at a point fixed relatively to said contact member and also normally connected at a fixed point to said frame, one of said members being movable toward and away from the other to adjust said sliding 45 connection.

2. The combination with a frame, of a rotary member carried thereby, a contact member, an adjustable operating means between said members, said operating means making 50 sliding connection with said rotary member and comprising a part of a pivotal joint one part of which joint is normally stationary on said frame and the other connected with said contact member at a point fixed relatively to 55 said contact member and also normally connected at a fixed point to said frame, one of said members being movable toward and away from the other to adjust said sliding connection.

60 3. The combination with a frame, of a rotary member carried thereby, a contact member, and adjustable operating means between said members, said means making sliding connection with said rotary member and comprising a part of a universal joint one part of 65

which joint is on said frame and the other connected with said contact member at a point fixed relatively to said contact member, one of said members being movable toward and away from the other to adjust said sliding connection. 70

4. The combination with a frame, of a rotary member carried thereby, a contact member, and adjustable operating means between said members, said operating means making 75 sliding connection with one of said members and comprising a part of a pivotal joint one part of which joint is normally stationary on said frame and the other connected with said contact member at a point fixed relatively 80 to said contact member, said rotary member being movable toward and away from said contact member to adjust said sliding connection.

5. The combination with a frame, of a rotary member carried thereby, a contact member, and adjustable operating means between 85 said members, said operating means making sliding connection with one of said members and comprising a part of a universal joint one 90 part of which joint is normally stationary on said frame and the other connected with said contact member at a point fixed relatively to said contact member, and means for moving one of said members toward and away from the other to adjust said sliding connection. 95

6. The combination with a frame, of a rotary member carried thereby, a contact member, a universal joint one part of which is normally stationary on said frame and the other connected with said contact member at a point fixed relatively to 100 said contact member, and adjustable means intermediate said rotary member and joint for actuating said contact member, said means having sliding 105 connection with said rotary member.

7. The combination with a frame, of a rotary member carried thereby, a contact member, a universal joint one part of which is on 110 said frame and the other connected with said contact member, and means intermediate said rotary member and joint for actuating said contact member, said means having sliding connection with said rotary member, and one of said members being movable toward and away from the other to adjust said sliding connection. 115

8. The combination with a frame, of a rotary member carried thereby, a contact member, a universal joint one part of which is normally stationary on said frame and the other connected with said contact member at a point fixed relatively to 120 said contact member, and means intermediate said rotary member and joint for actuating said contact member, said means having sliding connection with said rotary member, one of said members being movable toward and away from the other to adjust the sliding connection. 125

9. The combination with a frame, of a ro- 130

5 tary member carried thereby, a contact member, a pivotal joint one part of which is resiliently mounted connecting said frame and contact member, and operating means connecting said members.

10. The combination with a frame, of a rotary member carried thereby, a contact member, a pivotal joint one part of which is resiliently mounted connecting said frame and 10 contact member at a point fixed relatively to said contact member, operating connection between said members, and means for moving one of said members toward and away from the other to adjust said operating connections.

15. The combination with a frame, of a rotary member carried thereby, a contact member, a pivotal joint one part of which is resiliently mounted connecting said frame and 20 contact member, and operating means making sliding connection with one of the members, one of said members being movable toward and away from the other to adjust said sliding connection.

25. 12. The combination with a frame, of a rotary member carried thereby, a contact member, and operating means connected with said contact member and making radially sliding connection with said rotary member, 30 said operating means including a pivotal joint connecting said frame and contact member at a point fixed relatively to said contact member, one of said members being movable toward and away from the other to adjust 35 said sliding connection.

13. The combination with a frame, of a rotary member carried thereby, a contact member, and operating means connected with said contact member, said operating means 40 being also connected with said rotary member to slide obliquely to the axis of rotation thereof and including a pivotal joint connecting said frame and contact member at a 45 point fixed relatively to said contact member.

14. The combination with a frame, of a rotary member carried thereby and provided with a guideway oblique to the axis of rotation of said member, a contact device, and operating means connected with said contact device and engaging with said guideway, 50 said operating means including a universal joint connecting said frame and contact device at a point fixed relatively to said contact device.

15. The combination with a frame, of a rotary member carried thereby and provided with a guideway oblique to the axis of rotation of said rotary member, a contact member, operating means connected with said 60 contact member and in contact with said guideway, said operating means including a universal joint connecting said frame and contact member at a point fixed relatively to said contact member, and means for moving 65 one of said members toward and away from the other to adjust the connection with said guideway.

16. In a massage instrument, the combination with a motor, of a rotary member provided with a radial slot, a contact device, operating connections between said contact device and rotary member and engaging with the slot in the latter, and means for adjusting said rotary member to cause said connections 75 to adjust in said slot.

17. In a massage instrument, the combination with a motor, of a rotary member provided with a radial slot, a spring in said slot, a contact device, and operating connections 80 between said contact device and said rotary member and engaging with the slot in the latter.

In testimony whereof I have hereunto set my hand and affixed my seal in the presence 85 of the two subscribing witnesses.
